UNITED STATES PATENT OFFICE

150,519

DESIGN FOR A BUILDING UNIT

Pearl L. Schluttig, Kansas City, Mo.

Application November 19, 1946, Serial No. 134,890

Term of patent 7 years

(Cl. D13—1)

To all whom it may concern:

Be it known that I, Pearl L. Schluttig, a citizen of the United States, residing at Kansas City, in the county of Jackson and State of Missouri, have invented a new, original, and ornamental Design for Building Unit, of which the following is a specification, reference being had to the accompanying drawing, forming part thereof.

Fig. 1 is a front elevational view of a building unit showing my new design;

Fig. 2 is a rear elevation.

Fig. 3 is a side elevation.

I claim:

The ornamental design for a building unit, as shown.

PEARL L. SCHLUTTIG.
